IRONING MACHINE

George W. Wardwell, Jr., Nichols, Conn., assignor
to General Electric Company, a corporation of
New York

Application September 20, 1934, Serial No. 744,792

8 Claims. (Cl. 38—30)

My invention relates to ironing machines of the type in which ironing is effected by the pressure between pressing members.

In ironing machines of this type, it is customary to bias the pressing members away from the engaged or pressing position.

An object of my invention is to provide an ironing machine of this type with an improved arrangement for preventing sudden disengaging movement of the pressing members from the pressing position. For a consideration of what I believe to be novel and my invention, attention is directed to the following specification and the claims appended thereto.

15 In the accompanying drawings, Fig. 1 is a sectional end elevation of an ironing machine embodying my invention, with the shoe in the raised position; Fig. 2 is a sectional end elevation showing the shoe in the pressing position; Fig. 3 is a sectional front elevation of the ironing machine; Fig. 4 is an enlarged sectional view of one end of the operating shaft; Fig. 5 is a sectional view taken on line 5—5 of Fig. 4; and Fig. 6 is a sectional view taken on line 6—6 of Fig. 4.

20 Referring to the drawings, 1 indicates a buck across which the material to be ironed is placed and 2 indicates a heated shoe which is moved into pressing engagement with the buck.

The lower wall of the buck comprises a hollow casting 3 having longitudinal ribs 3a extending from the upper surface. Across the ribs and the edges of the casting is placed a plate 3b having perforations 4 therein which provides the upper wall of the buck. A pad 5 of textile material 25 is held in place over the upper wall of the buck by a pad cover 5a. The buck is slidably supported on a base 6 having a cylindrical depression 7 therein, within which a complementary projection 8 of the buck is adapted to slide. The base 30 and the buck are connected by a pin 9, one end of which is threaded into the buck, and the shank of which is slidable in the base 6 in a guide 10. A coil spring 11, arranged around the pin 9 between the buck and the base, is held in compression 35 between the buck and the base by the pin. The degree of compression of the spring is adjusted by threading the pin 9 into or out of the buck. By arranging the prestressed spring 11 between the buck and the base, the maximum pressure 40 exerted on the buck can be limited. An apron 6a is formed at the rear of the base and provides a space for receiving clothes.

45 During ironing, the moisture in the material being ironed is vaporized and passes through pad 5 and the perforations 4 into the inner part of

the buck where it is condensed and led through openings 12 into the cylindrical depression 7 of the base. Drain tubes 13 lead from the depression 7 of the base to pans 14, which are secured to the lower side of the base by studs 15, at either end of the base. Rubber bushings 16 are clamped between the lower end of the studs 15 and provide cushion supports for the base. A notch 14a is provided in the rear wall of each of the pans through which the water accumulated in the pans 10 may be emptied by tilting the machine.

The shoe 2 is made of metal such as aluminum and heated by heating units 17 which are cast into ribs on the top of the shoe in order to secure good heat conduction. The temperature of the 15 shoe is controlled by thermostats, the adjusting knobs 18 of which are shown in Fig. 3. The shoe is supported on the upper arm of a U-shaped carriage 19, the lower arm of which slides under the buck. The carriage is movable backward 20 with respect to the buck to allow more room for the operator to arrange material over the buck. The frame of the carriage is made of two pieces 19a and 19b which are secured together. A shaft 20, carried by the carriage at the front end of the 25 lower arm has wheels 21 which travel on ledges 22 formed in the sides of the pans 14 and support the front end of the carriage during forward and backward movement. The lower arm of the carriage fits between arms 23, projecting from the 30 pans 14, and rolls 24 journaled in the arms 23 engage the sides of the carriage and prevent endwise displacement of the carriage during the sliding movement. Projections 23a on the arms 23 engage ribs 23b on the side of the carriage 35 during the sliding movement and provide additional support for the carriage. At the rear end of the carriage is a wheel 25 which travels on the table or other surface which supports the ironing machine and supports the rear end of the carriage. A handle 26 is fixed to the carriage 19 for the convenience of the operator in shifting the carriage. The handle is held in place by a ball 40 27 which is spring pressed into a complementary notch in the handle.

The mechanism for moving the shoe into pressing engagement with the buck comprises a shaft 28 journaled in roller bearings 29 in the upper arm of carriage 19. The central portion of the shaft is cut away except for a portion 28a. A pin 30 extends across the cut away portion of the shaft and carries a ball bearing 31. The ball bearing 31 is eccentrically placed with respect to the center of the shaft 28 and the outer surface of the race of the ball bearing provides a cam which en- 45 50 55

gages a central transverse rib 32 on the shoe and moves the shoe into pressing engagement with the buck. When the shoe is in the engaged position as shown in Fig. 2, the cam is moved forward 5 past the center line of the force exerted by the shoe so that the shoe tends to remain in the engaged position. The portion 28a of the shaft provides a stop which limits the upward movement of the shoe as shown in Fig. 1. The cam 10 is rotated by a lever 33 connected to a hub 33a on the shaft 28. This lever is likewise held in position by a ball 34 which is spring pressed into engagement with a notch 35 in the lever.

In order to equalize the pressure exerted by 15 the shoe and to return the shoe to its raised position, independently movable levers or arms 36 are arranged at either side of the central rib 32 and connected to the intermediate portion of transverse springs 37. The ends of the trans- 20 verse springs 37 are connected to projections 37a on the shoe. The levers 36 are pivoted on the support 19 at 38 and are urged upwardly by springs 39 connected to the opposite ends of the levers. The vertical movement of the shoe is 25 guided by U-shaped guides 40 which are likewise arranged on either side of the rib 32 and connected to the transverse springs 37 intermediate their ends. The sides of the guides engage the shaft 28. By this arrangement vertical movement 30 of the shoe is guided by the guides 40 and the shoe is free to tilt in all directions in order to prevent unequal distribution of pressure between the shoe and the buck, such as might be caused by placing thicker material over one portion of the buck 35 than over another.

The springs 39 tend to move the shoe 2 to the raised position and, if the operating lever 33 were released after the upward movement was started, the upward movement might be too rapid and 40 the operator might be injured by the sudden movement of the operating lever 33. In accordance with my invention, this sudden movement of the operating lever and shoe is prevented by a speed responsive brake 42 arranged between 45 the shaft 28 and the upper arm of the carriage 19 which is more clearly shown in Figs. 4 and 5. This brake comprises a stationary cylindrical surface 43 which is secured to the carriage 19 and a surface 45 formed on the shaft 28 and inclined toward the cylindrical surface 43. A ball 46 is arranged between the surfaces 43 and 45 and is normally held by gravity against a projection or stop 47 secured to the shaft 28 at the inclined surface 45. During engaging movement 50 of the shoe, in which the lever 33 is rotated in a clockwise direction, as viewed in Figs. 2 and 5, the stop 47 prevents wedging of the ball 46 between the surfaces 43 and 45 and the brake therefore permits the free engaging movement of the 55 shoe. When the shoe is in the engaged position, the position of the brake is indicated by a dotted line in Fig. 5 and in this position a stop 48 secured to the cylindrical surface 43 limits the movement of the ball 46, and therefore limits the 60 movement of the operating lever 33. During normal disengaging movement of the operating lever 33, the ball 46 is held by gravity against the stop 47 and is not wedged between the surfaces 43 and 45. Normal disengaging movement of the 65 lever 33 is therefore not restrained by the brake. During sudden disengaging movement of the lever 33, such as might occur if the lever were released by the operator after the disengaging movement was started, the rotating part of the brake ac- 70 celerates faster than the ball 46 so that the ball 75

46 is not held against the stop 47 and the ball is wedged between the surfaces 43 and 45 retarding the disengaging movement. The action of the brake thus prevents a sudden disengaging movement of the operating lever which might injure the operator.

In the operation of the ironing machine, the carriage 19 which supports a shoe is moved to the rear to expose the upper surface of the buck and permit the operator to arrange the material 10 on the buck. The carriage is then moved forward by pulling on handle 26 to place the shoe above the buck in the position shown in Fig. 1. The operating lever 33 is then rotated in a clockwise direction as viewed in Fig. 2 so that the cam 15 31 engages the rib 32 of the shoe and forces the shoe into pressing engagement with the buck. The guides 40 guide the vertical movement of the shoe and the transverse springs 37 permit tilting of the shoe to equalize the pressure over the surfaces of the shoe. The arms 36 which are connected to the springs 37 resist the engaging movement of the shoe and tend to return the shoe and lever 33 to the disengaged position. The total pressure between the shoe and the buck is 20 limited by the prestressed spring 11 arranged between the base and the buck. To return the shoe to the position shown in Fig. 1, the operating lever 33 is rotated in a counter-clockwise direction elevating the cam 31 and permitting the 25 springs 39 to raise the shoe. As explained above, the brake 42 freely permits a slow disengaging movement of the operating lever 33 but prevents sudden disengaging movement of the lever.

What I claim as new and desire to secure by 35 Letters Patent of the United States is:

1. An ironing press comprising a pair of pressing members, means including a lever for effecting engagement and separation of said pressing members, means including a spring for returning said lever to the disengaged position, a brake having a fixed member and a relatively rotatable member connected to said lever, said brake having a cylindrical surface on one of said members and a surface inclined to said cylindrical surface 45 on the other of said members, a ball between said surfaces, and means for preventing wedging of said ball between said surfaces during engaging movement of said lever, said ball being subjected to a force tending to move it at a limited 50 instantaneous speed relative to said fixed member whereby it will become wedged between said surfaces upon disengaging movement of the lever at an instantaneous speed greater than said limited instantaneous speed.

2. An ironing press comprising a pair of pressing members, means including a lever for effecting engagement and separation of said pressing members, means including a spring for returning said lever to the disengaged position, a brake having a fixed member and a relatively rotatable member connected to said lever, said brake having a cylindrical surface on one of said members and a surface inclined to said cylindrical surface on the other of said members, a ball between said 65 surfaces, a projection on said inclined surface, and means for holding said ball against said projection during engagement movement of said lever, said ball being subjected to a force tending to move it at a limited instantaneous speed relative to said fixed member whereby it will become wedged between said surfaces upon disengaging movement of the lever at an instantaneous speed greater than said limited instantaneous speed.

3. In an ironing press, a pair of pressing mem-

bers, pressure applying mechanism including an operator operated lever for effecting pressing engagement and disengagement of the pressing members, means for biasing said lever to a position disengaging the pressing members, and braking means operatively associated with said lever for resisting the disengaging movement of the lever, said braking means being normally ineffective to resist movement of the lever and being rendered effective in response to a limited instantaneous speed of the lever whereby the speed of disengaging movement is retarded.

4. In an ironing press, a buck, a shoe, means including a lever for moving the shoe into pressing engagement with the buck, spring means for returning the lever to the disengaged position, means for holding the pressing members in engagement in opposition to said spring means, said holding means being operatively associated with said lever whereby it is rendered ineffective upon movement of the lever to effect disengagement of the pressing members, and a brake operatively associated with said lever for resisting disengaging movement of the lever, said brake being normally ineffective to resist movement of the lever and being rendered effective in response to a limited instantaneous speed of the lever whereby the speed of disengaging movement is retarded.

5. In an ironing press, a buck, a shoe, means including a lever for moving the shoe into pressing engagement with the buck, spring means for returning the lever to the disengaged position, means for holding the pressing members in engagement in opposition to said spring means, said holding means being operatively associated with said lever whereby it is rendered ineffective upon movement of the lever to effect disengagement of the pressing members, and a brake operatively associated with said lever for resisting disengaging movement of the lever, said brake being normally ineffective to resist movement of the lever and being constructed and arranged to be rendered effective to resist disengaging movement of the lever in response to a predetermined acceleration of the lever whereby excessive speed of the disengaging movement of the lever is prevented.

6. In an ironing press, a pair of pressing members, pressure developing mechanism for effecting pressing engagement of the pressing members, spring means for effecting separation of the

pressing members, and braking means for resisting separation of the pressing members, said braking means being normally ineffective to resist separation of the pressing members and being rendered effective in response to a limited instantaneous speed of separation of the pressing members.

7. In an ironing press, a pair of pressing members, pressure developing mechanism for effecting pressing engagement and disengagement of the pressing members, an operator operated lever for actuating said mechanism, biasing means for moving the lever to the disengaged position, said mechanism including an over-center device operatively associated with said lever whereby said lever will be held in the position effecting engagement of said pressing members upon movement thereto and whereby said over-center device will be rendered ineffective upon movement of said lever therefrom, and braking means operatively associated with said lever for resisting sudden disengaging movement on the lever, said braking means being normally ineffective to resist movement of the lever and being constructed and arranged to be rendered effective to resist disengaging movement of the lever in response to a predetermined acceleration of the lever whereby excessive speed of separation of the pressing members is prevented.

8. In an ironing press, a pair of pressing members, pressure developing mechanism for effecting pressing engagement of the pressing members, spring means for effecting separation of the pressing members, and braking means for resisting separation of the pressing members, said braking means comprising relatively movable friction surfaces operatively associated with said pressing members so as to be moved thereby relative to each other, and a friction member adapted to be moved into engagement with said surfaces upon relative movement of said surfaces, said friction member being subjected to a force tending to hold it normally out of engagement with said surfaces and to move it at a limited instantaneous speed whereby it will be moved into engagement with said surfaces upon relative movement of said friction surfaces at an instantaneous speed greater than said limited instantaneous speed.

GEORGE W. WARDWELL, JR. 50
